UNITED STATES PATENT OFFICE.

GEORGE H. JENKINS, OF OAK PARK, ILLINOIS.

BOOKBINDING DEVICE.

1,235,322.

Specification of Letters Patent. Patented July 31, 1917.

Application filed July 8, 1914. Serial No. 848,840.

To all whom it may concern:

Be it known that I, GEORGE H. JENKINS, a citizen of the United States, residing at Oak Park, in the county of Cook and State 5 of Illinois, have invented certain new and useful Improvements in Bookbinding Devices, of which the following is a specification.

This invention relates to a device for binding in a convenient form loose leaves, correspondence papers, etc., and is concerned with the particular design and arrangement of the mechanism by which the binding operations are carried into effect.

15 Among the principal objects of my invention, is the provision of means for retaining a stack of leaves in convenient position for treatment preparatory to binding; means for adjusting the device to papers of different size; and means for conveniently handling a stack of leaves in the various positions required. The invention further consists in numerous other features of construction and combinations of parts as will 20 25 more fully hereinafter appear.

In the drawings:

Figure 1 is a perspective view of a device for alining and evening a stack of leaves preparatory to binding;

30 Fig. 2 is a plan view of the device in which the papers are bound;

Fig. 3 is a side elevation of the device;

Fig. 4 is an end elevation of the same;

35 Fig. 5 is a side elevation of the device with one section swung into vertical position; and

Figs. 6 and 7 are detail views of the locking means employed for the movable evener on the device.

40 Preparatory to binding leaves or papers, it is desirable to even up and aline the edges to be bound. For this purpose, a convenient device is shown in Fig. 1, representing a box-like structure having side walls 8 and 9 disposed at right angles to each other, and a base disposed at right angles to each of said walls. For convenience in manipulation, the base 10 is shown obliquely inclined, and the sides 8 and 9 are tilted correspondingly. In carrying into effect the present invention, I prefer to utilize a strap 11 of any suitable material, such as webbing or tape, to tie around covers 12 and a stack of leaves 13 between the same. The use of such 45 50 55 tying means is not, however, essential. Slots 14 are shown arranged in the base and in

one of the side walls, within which such a strap may lie, thereby permitting leaves to lie squarely against the walls of the structure.

60

After alinement has been effected, the paper is transferred to the binding device which constitutes the substance of my present invention. As shown in Fig. 2, this comprises a base member 15 which for purposes of use should preferably be secured to a fixed base or table 16, and a swinging base member 17 joined to the member 15 as by a hinge connection 18. In Fig. 5 is shown the relative positions of the members 15 and 17 when a swinging movement has been executed, one or more links 19 pivotally secured to one member as at 20 engaging with a pin 21 on the other member to maintain the parts of the base in such right angular relation when desired.

65

The leaves when placed upon the portion 17 are alined in longitudinal position for binding by means of a movable evener 22 which I prefer to construct of two telescoping parts to enable leaf stacks of varying thicknesses to be accommodated. Preferably the upper edge of this evener is provided with forwardly extending portions to engage with the upper surface of the stack of leaves 80 undergoing treatment. As appears best in Fig. 6, the ends of the evener 22 extend downwardly to provide arms 23 which partly overlie the sides of the base. These arms each terminate in an elongated portion 90 95 100 105 110 24 which is parallel to the base, and carry an inturned member 25 arranged to lie within a groove or slot 26 formed in the side wall of the base. A ratchet bar 27 is provided on the inner side of the groove 26 with which a catch 28 of spring material engages, the catch being mounted on the elongated portion 24 of the arm 23. This construction insures a maintenance of the evener 22 in constant vertical position with provision for adjustment forwardly or rearwardly on the portion 17 of the base.

Near the swinging edge of the base member 17, I have provided a compression device which, for purposes of illustration, is shown as consisting of two posts 29 exteriorly threaded to receive a thumb screw 30, a compression plate or bar 31 being arranged to move upon the posts and be guided thereby. The operation and construction of this compression device is quite similar to that shown and described in my

pending application, Serial No. 837,899, filed May 11, 1914, so that further description is not deemed necessary. For the sake of convenience, these posts should be attached to the base member 17 at the extreme side edges thereof, or if preferred at places 32 which extend out beyond the sides of said member to leave as wide a space as possible for paper leaves to lie therebetween. I have also provided a second evener 33, operating in a direction transverse to the evener 22, and having an arm 34 arranged to engage with a rack 35 disposed within a groove in the member 17. This feature of construction is also disclosed in my pending application referred to.

To the swinging edge of the base member 17, as through the medium of thumb screws 36 is removably secured a member 37 extending vertically and parallel to the evener 22. This member is formed with a horizontal portion 38 which lies in substantially the same plane with the top surface of the base members. The vertical portion of the member 37 is slotted as at 39 from the top edge thereof down to and through the horizontal portion thereof, the slits being obliquely inclined in a horizontal plane to form, in effect, a miter plate, as best shown in Fig. 2. That portion of the member 37 which lies in juxtaposition with the swinging edge of the member 17 is integral from end to end as clearly appears in Fig. 4.

The binding operation, as contemplated in the device herein disclosed, takes place substantially as follows: A stack of leaves first aligned, and tied if preferred, are arranged upon the base member 17 with the edge to be bound in square engagement with the member 37. Should the leaves when laid in position require further alinement, the eveners 22 and 33 are adjusted for this purpose. It is, of course, usual in operations of this kind for the leaves to be bound between suitable covers, and it is expected, therefore, that covers should be so arranged. While in this position, the thumb screws 30 are manipulated to bring the bar or plate 31 down upon the stack of leaves with great pressure, thereby facilitating the further binding operations required.

The base member 17 is next swung around into vertical position as appears in Fig. 5, the link 19 engaging with the pin 21 to lock the members 15 and 17 in fixed relative positions. Oblique cuts or slits are then made in the edges of the leaves in the planes determined by the slits 39, through the use of a saw or other suitable device. The horizontal portion 38 of the member 37 for this operation functions as a miter plate, and determines the angle at which the slits shall be cut as well as the depth thereof. The member 37 is next detached from the base member as its presence no longer is required,

the pressure effected through the bar 31 is relieved, and the evener 22 is advanced to raise the stack into more convenient operating position.

To complete the binding operation, several additional steps are contemplated which may, however, in practice be modified according to the requirements of use. Among these is the application of a heavy paste or glue which has both adhesive and filling properties over the edges of the leaves and in the slits which have been cut therein. A suitable cord or string is then passed through the saw cuts and tied to bind the edges of the leaves in permanent form. The saw cuts have been described as disposed at an angle to prevent displacement of a tying cord, but it is obvious that the same may be parallel and perpendicular to the edge in which they are cut without in any way impairing the efficiency of the tying means used.

I claim:

1. A device of the kind described, embodying, in combination, a base on which a quantity of leaves may be stacked, a miter-plate removably secured to the base having one of its faces substantially even with the upper surface of the base, means carried by the miter plate for positioning a stack of leaves upon the base in operative relation to the miter-plate, and means carried by the base for pressing the leaf stack upon the base and miter-plate, substantially as described.

2. A device of the kind described, embodying, in combination, a base on which a quantity of leaves may be stacked, a miter-plate removably secured to the base having one of its faces substantially even with the upper surface of the base, means carried by the miter-plate for positioning a stack of leaves upon the base in operative relation to the miter-plate consisting of an upstanding wall with which one edge of the stack of leaves may engage, and means carried by the base for pressing the leaf stack upon the base and miter-plate consisting of a pair of threaded posts secured to the base, a presser bar extended between the posts, and members threaded upon the posts for exerting pressure upon the bar in the direction of the leaf stack, substantially as described.

3. A device of the kind described, embodying, in combination, a base on which a quantity of leaves may be stacked, a miter plate secured to the base and substantially even with the upper surface thereof, and means for determining the operative position of the leaf stack relative to the miter plate, substantially as described.

4. A device of the kind described, embodying, in combination, a base, an evener upon the base for retaining in stacked relation a quantity of leaves with one edge of the stack overlapping one edge of the base,

means carried by the base for applying pressure to the stacked leaves in proximity to the said overlapping edge thereof, and means carried by the base for guiding the movement of a cutting implement operating in the overlapping edge of the leaf stack, substantially as described.

5. A device of the kind described, embodying, in combination, a base on which a quantity of leaves may be stacked, a miter plate secured to one edge of the base, substantially even with the upper surface thereof, means carried by the base for evening the leaves, said means serving also to hold 10 the leaf stack in operative position relative to the miter plate, substantially as described.

6. A device of the kind described, embodying, in combination, a base upon which a quantity of leaves may be stacked one upon 15 the other, and an evener adjacent one edge of the stack carried by the base, the upper edge of the evener being turned to engage with the upper side of the stack to hold the same firmly upon the base, substantially as 20 described.

25. 7. A device of the kind described, embodying, in combination, a base, a miter

plate secured to one edge of the base, a portion of said plate lying in substantially parallel relation and in the same plane with the 30 upper surface of the base, and another portion of the plate being perpendicular to the base, the miter plate having slots formed in the portion lying in the same plane with the upper surface of the base to determine 35 the direction in which a cutting implement shall operate, substantially as described.

8. A device of the kind described, embodying, in combination, a base, a miter plate secured to one edge of the base, a portion of 40 said plate lying in substantially the same plane with the upper side of the base, and a portion perpendicular thereto, said plate being provided in the portion parallel to the base with a plurality of slots which converge, 45 and in the portion which is perpendicular to the base with a plurality of slots which are parallel and which connect respectively with the converging slots, substantially as described.

GEORGE H. JENKINS.
